Primary Examiner — David G Muller*Assistant Examiner* — Nathan M Johnston*(74) Attorney, Agent, or Firm* — Eversheds Sutherland (US) LLP(57) **CLAIM**

I claim the ornamental design for an item dispensing workstation, as shown and described.

DESCRIPTION

FIG. 1 is a perspective view showing our new design for an item dispensing workstation;

FIG. 2 is a front view showing the design of FIG. 1;

FIG. 3 is a rear view showing the design of FIG. 1;

FIG. 4 is a top view showing the design of FIG. 1;

FIG. 5 is a bottom view showing the design of FIG. 1;

FIG. 6 is a right-hand view showing the design of FIG. 1; and,

FIG. 7 is a left-hand view showing the design of FIG. 1.

In FIGS. 1-7, the broken lines and shading are for purposes of illustration only, and do not form a part of the claimed design.
